UNITED STATES PATENT OFFICE.

AARON A. GOLDSTEIN, OF BUFFALO, NEW YORK, ASSIGNOR OF ONE-HALF TO SOLOMON E. KOPLAR, OF BUFFALO, NEW YORK.

CUFF BUTTON.

Application filed February 25, 1924. Serial No. 694,989.

To all whom it may concern:

Be it known that I, AARON A. GOLDSTEIN, a citizen of the United States of America, and resident of the city of Buffalo, State 5 of New York, in the United States of America, have invented certain new and useful Improvements in Cuff Buttons, as described in the following specification and illustrated in the accompanying drawings, that 10 form part of the same.

The principal objects of this invention are to improve and simplify the construction of cuff buttons of the type in which two members are temporarily locked together to hold the cuff from accidental separation, and to provide an effective means for 15 unlocking the button which will be easy to operate and will ensure the separation of the button members.

20 The principal feature of the invention consists in the novel manner of effecting the withdrawal of the locking member from between the projecting stud of one button and the throat of the other button by means 25 of a plunger adapted to push against the locking member.

A further important feature consists in forming the stud member of a drawn tubular structure.

30 In the drawings Figure 1 is an enlarged sectional view of a button constructed in accord with this invention shown in the locked position.

Figure 2 is a view similar to Figure 1 35 showing the releasing plunger pressed in to remove the locking member from locking engagement with the stud.

Figure 3 is a perspective detail of the locking member.

40 Figure 4 is a perspective detail of the stud before being secured in the button.

The type of button to which this invention is applied is that type where a stud secured in or forming part of one member of the 45 button is inserted into a socket in the other button member and is locked therein by a movable member which is operated to release the stud.

In the construction shown the button 50 members 1 and 2 are similarly formed with converging body portions 3 having the crown plates 4 at the larger ends and the flaring plates 5 at the inner ends.

55 A stud 6 is secured in one of the button members, being here shown of a tubular con-

struction preferably drawn to shape with a head 7 converging to form a neck 8 and having a shank 9 formed with a shoulder 10 to abut the plate 5. The inner tubular end 11 is swaged outwardly in the throat 12 of the member 5 and is thus rigidly and permanently secured therein.

A hole 13 is formed in the outer end of the head 7 and a pin 14 is slidably arranged in the stem and extends through the hole 60 13. The pin 14 is formed with a head 15 which abuts the inner face of the crown plate 4 and the head is provided with a reduced portion 16 which extends through a hole 17 in the crown plate and presents the 65 means for pressing the pin inwardly. A coil spring 18 encircles the pin between the head 15 and a shoulder 19 formed at the inward end of the stud and holds the pin 70 against the crown plate.

The other button member has arranged therein a locking member in the form of a chuck having the convergent fingers 20 extending from the edge of a plate 21, said 80 fingers being adapted to fit into the throat 22 and to closely surround the neck of the stud and prevent the withdrawal of the head when it has been entered therein.

The locking member is formed of spring 85 material and the fingers will spread apart to allow the stud head to enter when the said member is moved away from the restricting throat. An arched spring 23 is arranged within the button to engage the locking member 21 to hold it into the throat 90 but the spring readily yields to allow the locking member to recede from the throat when the stud head is pushed into the throat, but upon the fingers spreading apart under the pressure of the stud the spring 23 reacts and moves the locking fingers into the 95 throat around the neck of the stud and the button is then locked.

In order to release the lock the pin 14 is pushed inwardly and the inner end presses 100 against the plate 21 of the locking member releasing the lock and as the lock releases the head of the stud the reaction of the arched spring, which is depressed by the inward movement of the pin, throws the button members apart.

The construction herein shown and described is such as to enable the parts being manufactured and assembled at a remarkably low cost and the article produced is 110

strong and durable and very efficient in operation.

What I claim as my invention is:—

1. In a cuff button, the combination with a pair of button members, one having a stud projection formed with a neck portion and the other having a convergent throat, and a locking member arranged in said throat and engaging the neck of said stud, of means carried by the stud member adapted to engage and release said locking member from its locking engagement with the stud.
2. In a cuff button, the combination with a pair of button members, one having a stud projection formed with a neck portion and the other having a convergent throat, and a locking member arranged in said throat and engaging the neck of said stud, of a plunger slidably supported in said stud member adapted to engage and release said locking member from locking engagement with the stud.
3. In a cuff button, the combination with a pair of button members, one having a stud projection formed with a neck portion and the other having a convergent throat, and an axially moveable locking member arranged in said throat and engaging the neck of said stud, of a plunger extending axially through said stud the protruding end being adapted to engage and move the locking member out of locking engagement with said stud.
4. In a cuff button, the combination with a pair of button members, one having a stud projection formed with a neck portion and the other having a convergent throat, a locking member arranged in said throat and engaging the neck of said stud, of a pin slidably arranged in said stud and projecting

through the end thereof to engage the locking member, said pin having a shoulder, a spring engaging the shoulder of said pin, and a reduced end on said pin extending beyond the button.

5. In a cuff button, a button member formed with a convergent throat, a stud drawn into tubular form and having one end inserted in and expanded into said throat, a mating button member adapted to receive said stud, means for temporarily locking said stud in the mating member and means extending through said tubular stud and engaging said locking means to release the same.

6. In a cuff button, a socket member, a stud member adapted to enter the socket member, means for locking the stud member within the socket member, means for releasing the locking member, and a spring means for separating the members upon the release of the locking means.

7. In a cuff button, a socket member, a stud member adapted to enter the socket member, a spring actuated chuck adapted to engage and lock the stud member, and means for moving said chuck to clear the stud member and to cause the socket member to spring away from the stud member.

8. In a cuff button, a socket member, a chuck in said socket member, a spring in said socket member holding said chuck in position, a stud member adapted to enter

said chuck, and a movable pin extending through said stud and adapted to disengage the chuck from the stud and depress the spring to cause the socket member to withdraw from the stud member.

AARON A. GOLDSTEIN.
